(57) **CLAIM**

The ornamental design for a pregnancy test midstream as shown and described.

DESCRIPTION

FIG. 1 is a perspective view of a pregnancy test midstream showing the new design;

FIG. 2 is another perspective view thereof;

FIG. 3 is a front view thereof;

FIG. 4 is a back view thereof;

FIG. 5 is a left side elevational view thereof;

FIG. 6 is a right side elevational view thereof;

FIG. 7 is a top view thereof;

FIG. 8 is a bottom view thereof;

FIG. 9 is an enlarged detail view taken from the encircled area 9 in FIG. 1; and,

FIG. 10 is a perspective view showing a pregnancy test midstream opened for use.

The dashed broken lines in the figures depict portions of the pregnancy test midstream that form no part of the claimed design. The dot-dash broken lines depict the bounds of the enlarged views and form no part thereof.

1 Claim, 10 Drawing Sheets
